To all whom it may concern:

Be it known that I, JESSE A. CRANDALL, a citizen of the United States, residing at Brooklyn, in the county of Kings, State of New York, 5 have invented certain new and useful Improvements in a Design for a Rattle, of which the following is a specification, reference being had therein to the accompanying drawing.

The drawing represents a view of my design. 10 The leading feature of the design consists of the terminal ornamentation representing a hat upon a shield.

A is a rattle having at its end the repre-

sentation of a hat, (designated by the letter B.) Forming a support for the hat is a shield-like 15 portion C.

What I claim is—
